(57) **CLAIM**

The ornamental design for a wood turning tool handle, as shown and described.

DESCRIPTION

FIG. 1 is a perspective view of a wood turning tool handle of the present invention shown in a use state;

FIG. 2 is a side view of the wood turning tool handle;

FIG. 3 is an end view of the wood turning tool handle;

FIG. 4 is a rear view of the wood turning tool handle; and,

FIG. 5 is an exploded perspective view of the wood turning tool handle.

The broken lines shown represent environmental subject matter and form no part of the claimed design.
